HAND OPERATED WEED CUTTER

Oscar E. Erickson, 1933 E. 27th St.,
Hibbing, Minn. 55746

Filed July 6, 1970, Ser. No. 23,828

Term of patent 14 years

Int. Cl. D8—01

U.S. Cl. D8—7

FIG. 1 is a perspective view of a hand operated weed cutter embodying my new design.

FIG. 2 is a side elevational view thereof.

FIG. 3 is a front elevational view thereof.

I claim:

The ornamental design for a hand operated weed cutter, as shown.
